UNITED STATES PATENT OFFICE.

CHARLES J. L. MEYER, OF CHICAGO, ILLINOIS.

SECTIONAL FEED AND PRESSER ROLL.

SPECIFICATION forming part of Letters Patent No. 717,593, dated January 6, 1903.

Application filed January 3, 1898. Serial No. 665,375. (No model.)

To all whom it may concern:

Be it known that I, CHARLES J. L. MEYER, of Chicago, in the county of Cook and State of Illinois, have invented certain new and useful Improvements in Sectional Feed and Presser Rollers; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The main objects of my invention are to insure simultaneous and equal engagement of different parts of a feed or presser roller with a plurality of strips or pieces of material or with different parts of strips or pieces varying in thickness transversely and to simultaneously feed a plurality of strips or pieces of lumber or other material of different or varying thicknesses to a planer or other machine or to yieldingly hold them in the proper position to be operated upon by a planer-knife or other tool.

The invention consists, essentially, of a roller composed of sections movable separately and transversely on a common shaft through which rotary movement is imparted to the several sections and separately-yielding tension devices bearing upon the peripheries of the several sections, and of certain novel details in the construction and arrangement of component parts of the device hereinafter particularly described, and pointed out in the claims.

In the accompanying drawings like letters designate the same parts in the several figures.

Figure 1 is a vertical longitudinal section on the line 1 1, Fig. 2, of a portion of a planer to which my improved roller mechanism is applied. Fig. 2 is an end elevation of the machine as viewed from the left with reference to Fig. 1. Fig. 3 is an enlarged vertical cross-section on the line 3 3, Fig. 2, of the roller mechanism. Fig. 4 is an axial section, on a still larger scale, of a portion of one of the sectional rollers. Fig. 5 is a cross-section of one of the rollers, showing a modification of one of the tension devices employed therewith. Fig. 6 is a cross-section of one of the

roller-shafts and an end elevation of one of the roller-sections, showing a modified construction thereof. Fig. 7 is a side elevation, on an enlarged scale, of one of the tension-rollers, and Fig. 8 is a similar view of a modified form thereof.

Referring to Figs. 1 and 2, A designates a portion of the frame of a planer provided with a work-supporting bed B. C designates the planer-knife, and D the lower feed-rollers, projecting on their upper sides slightly above the bed B through openings therein.

The foregoing parts are or may be of the usual construction and arrangement employed in this class of machines and are shown merely for the purpose of more clearly explaining my improved roller mechanism, which may be applied to any machine in which a sectional feed or presser roller is desirable.

E is a vertically-adjustable slide or frame supported and guided at the ends in standards F F on the main frame A and provided with bearings for a driving-shaft G, which extends horizontally over and across the bed B. The slide E is adjusted by vertical screws e, engaging therewith at or near the ends, and a horizontal crank-shaft e', which has bearings on the upper ends of the standards F and is connected with said screws by bevel-gears incased in boxes e² and not shown, one end of the shaft e' being squared, as shown in Fig. 2, to receive a crank or hand wheel.

H H are the roller-frames, formed with sleeves g, by means of which they are pivotally mounted upon the shaft G. They are also formed or provided at their ends, as shown in Figs. 2 and 4, with boxes g', which support the roller-shafts I parallel with the driving-shaft G, on opposite sides thereof. The roller-shafts I are connected at or near their ends with the driving-shaft G by gears i i and g², as shown in Fig. 1, and the driving-shaft G is provided at one end, as shown in Fig. 2, with a gear g³, through which it is driven from any convenient part of the machine.

The feed or presser rollers are composed of sections J J, loosely mounted upon the shafts I end to end and held in place thereon by nuts j j, as shown in Figs. 2 and 4. The holes in the several roller-sections are made somewhat larger than the shafts I, so as to admit

of a limited radial movement of said sections on said shafts, each section being movable independently of the other sections. They are compelled to turn with said shafts by 5 splines $i'i'$, which loosely engage with notches in the bores of the roller-sections, as shown in Fig. 3, or in place of the splines the roller-shafts and the holes in the roller-sections may be made square, as shown in Fig. 10 6, or of any other shape that will permit the sections to move radially a limited distance, but will compel them to turn with said shafts.

K K are slides carried by the roller-frames H above the sectional rollers and movable in 15 said frames toward and from said rollers, the number and arrangement of said slides corresponding with the number and arrangement of the roller-sections J. These slides are held and guided in their proper relative 20 positions between vertically-disposed faces on the roller-frames and bars or plates h, connected therewith by squared shoulder-bolts h'.

L represents rollers which may be made 25 double, as shown in Fig. 7, or single, as shown in Fig. 8, and are journaled parallel with the roller-shafts I in the slides K, so as to bear upon or against the peripheries of the roller-sections J. They are supported and held in 30 their proper relations to each other by the squared shoulder-bolts h', as shown in Fig. 4. When the roller-sections J have transversely-corrugated faces, as shown in Fig. 3, they are also formed with circumferential 35 grooves, as shown in Figs. 2 and 4, to receive and afford proper bearings for the peripheries of the rollers L.

The rollers L are yieldingly pressed and held against the roller-sections J by spiral 40 springs M, interposed between the slides K, and adjusting-screws N, which are threaded in overhanging portions of the roller-frames H perpendicularly to the axes of said rollers.

The slides K, rollers L, springs M, and 45 screws N constitute yielding and adjustable tension devices by which the several roller-sections J are normally held in line with each other against their shafts I opposite the bed B and the working faces of said roller-sections and by which said roller-sections are 50 allowed to yield independently of each other away from the bed, so as to adapt themselves to and to insure their even engagement with strips of different thicknesses or stuff varying in thickness transversely, as illustrated in Fig. 4.

Each of the roller-frames H is adjustably and yieldingly connected with the slide E above the driving-shaft G by horizontally-disposed bolts or rods O, secured in said frames and passing loosely through a cross-piece of said slide, and by spiral springs P, interposed between said frames and cross-piece around said bolts, as shown in Fig. 3, 60 so as to permit each of the sectional rollers to yield upwardly independently of the other. By means of the nuts on the bolts O the ten-

sion of the springs P may be adjusted, and the extent to which the rollers J are raised or lowered by such adjustment may be compensated for by lowering or raising the slide E. 70

In place of the springs M and adjusting-screws N arms m, pivoted to the roller-frames H, so as to bear on the tension-roller slides K and provided with adjustable 75 weights n, as shown in Fig. 5, may be substituted.

By means of the tension devices hereinbefore described any desired degree of pressure may be applied to the roller-sections J, 80 and this pressure may be readily adjusted for any or all of the sections, as desired. This is a great advantage over those sectional feed and presser rollers in which the tension devices consist of springs placed inside 85 of the roller-sections between them and the shaft on which they are mounted and in which there is no provision for adjusting the tension of the springs, and their strength is necessarily limited and apt to deteriorate. 90

For the purpose of holding a plurality of strips or pieces of material in the proper positions on the bed B to be engaged separately by the roller-sections J the bed is provided on the upper side, as shown in Figs. 1 and 2, 95 with longitudinal guides or parting-strips bb, arranged in line with the divisions between the roller-sections J.

The corners of the roller-sections J are rounded or beveled, as shown most clearly in 100 Fig. 4, to prevent breaking, gouging into, or marring the corners of strips or pieces of material with which the roller-sections would otherwise engage but slightly.

I do not wish to be understood as limiting 105 myself in the application of my improved sectional roller to any particular machine, as it is applicable to any machine in which a sectional feed or presser roller is desirable. Neither do I wish to be understood as limiting 110 myself to the details of construction and arrangement shown and described, as they may be variously modified within the spirit and intended scope of my invention.

I claim—

1. In combination with a roller composed 115 of sections mounted and radially movable, independently of each other, upon a common shaft through which rotary movement is imparted to the several sections, of independently-yielding tension devices bearing upon the peripheries of the several roller-sections and pressing them toward the work, substantially as and for the purposes set forth.

2. In combination with a roller composed 125 of sections mounted and radially movable independently of each other upon a common power-transmitting shaft, and means for imparting rotary movement to the several roller-sections through said shaft, of independently- 130 yielding tension devices bearing on the peripheries of the several roller-sections, and means of independently adjusting the pressure of each tension device upon its roller-

section, substantially as and for the purposes set forth.

3. In combination with a roller composed of sections mounted and radially movable independently of each other upon a common power-transmitting shaft, through which rotary movement is imparted to the several sections, of tension-rollers bearing on the peripheries of the roller-sections, and means for yieldingly pressing each tension-roller, independently of the others, against its roller-section, substantially as and for the purposes set forth.

4. In combination with a roller composed of sections mounted and radially movable independently of each other upon a common power-transmitting shaft, of slides corresponding in number and arrangement with the roller-sections and also movable transversely to the axis of the roller, tension-rollers journaled in said slides and bearing against the peripheries of the roller-sections, and springs tending to force said slides toward the axis of the roller and to yieldingly hold the several roller-sections against the work, substantially as and for the purposes set forth.

5. In combination with a roller composed of sections mounted and radially movable independently of each other upon a common power-transmitting shaft, of slides corresponding in number and arrangement with the roller-sections and also movable transversely to the axis of the roller, tension-rollers journaled in said slides parallel with the axis of the sectional roller and movable transversely thereto, springs pressing said slides toward the sectional roller and yieldingly holding the tension-rollers in engagement with the peripheries of the several roller-sections, and screws for adjusting the tension of the several springs independently of each other, substantially as and for the purposes set forth.

45 6. The combination of a roller-shaft, a number of rotary power-transmitting sections mounted thereon and each movable independently of the others transversely upon said shaft, but compelled to turn therewith, and independently-yielding tension devices bearing against the peripheries of the several roller-sections and tending to press them toward said shaft and to hold them normally in line with each other, substantially as and for the purposes set forth.

7. The combination with a suitable frame provided with a work-supporting bed, of a driving-shaft supported in a frame adjustable toward and from said bed, a roller-frame pivotally mounted upon said shaft and yieldingly connected with said adjustable frame, a roller composed of sections mounted and radially movable independently of each other upon a power-transmitting shaft which is supported in said roller-frame parallel with said driving-shaft, and independently-yielding tension de-

vices bearing against the roller-sections and tending to press them toward said bed and to hold them in line with each other upon the roller-shaft, substantially as and for the purposes set forth.

8. The combination with a suitable frame provided with a work-supporting bed, of a sliding frame adjustable toward and from said bed, screws for adjusting said sliding frame, a driving-shaft carried by said frame transversely across and over said bed, two roller-frames pivotally mounted upon said shaft and yieldingly connected with said adjustable frame, two roller-shafts having bearings in said roller-frames on opposite sides of and parallel with said driving-shaft, which is geared with said roller-shafts; roller-sections mounted upon and rotatably engaged by said roller-shafts and radially movable thereon independently of each other, and independently-yielding tension devices mounted on said roller-frames and bearing against the peripheries of the several roller-sections, substantially as and for the purposes set forth.

9. The combination with a suitable work-supporting frame or bed, of a sliding frame movable toward and from said bed, screws for adjusting said sliding frame, a driving-shaft journaled in said sliding frame crosswise of the bed, two roller-frames pivotally mounted upon said driving-shaft and having adjustable yielding connections with said sliding frame, two roller-shafts carried by said roller-frames on opposite sides of and parallel with said driving-shaft and connected therewith by gears, rollers composed of sections which are mounted and capable of a limited radial movement upon said roller-shafts independently of each other, but are compelled to turn with said shafts, tension-rollers bearing against the peripheries of the roller-sections and means for yieldingly pressing said tension-rollers against the roller-sections and forcing them toward said bed, substantially as and for the purposes set forth.

10. The combination with a work-supporting bed provided with longitudinal division and guiding strips, of a roller composed of independently and radially yielding sections, the divisions between the roller-sections being arranged in line with said parting and guiding strips, substantially as and for the purposes set forth.

11. A roller composed of independently and radially yielding sections, mounted close together end to end upon a common shaft and having their corners rounded or beveled, substantially as and for the purposes set forth.

In testimony that I claim the foregoing as my own I affix my signature in presence of two witnesses.

CHARLES J. L. MEYER.
